The Schedule referred to in these Letters Patent and making part of the same.

TO ALL WHOM IT MAY CONCERN:

Be it known that we, GARRETTSON SMITH and HENRY BROWN, of Philadelphia, county of Philadelphia, State of Pennsylvania, have invented or produced a new and original Design for the Plates of a Cooking-Stove; and we do hereby declare that the accompanying drawing, and the following explanation thereof, form a full, clear, and exact description of the said design.
